Patented Mar. 16, 1926.

1,577,181

UNITED STATES PATENT OFFICE.

WILLIAM EDWARD CROWE, OF CHICAGO, ILLINOIS, ASSIGNOR TO THE PRISMATONE COMPANY, INC., OF CHICAGO, ILLINOIS, A CORPORATION OF NEW YORK.

METHOD OF PRODUCING INTAGLIO PRINTING PLATES OR CYLINDERS.

No Drawing.

Application filed January 9, 1925. Serial No. 1,498.

To all whom it may concern:

Be it known that I, WILLIAM EDWARD CROWE, a subject of the King of England, and resident of Chicago, county of Cook, 6 and State of Illinois, have invented certain new and useful Improvements in Methods of Producing Intaglio Printing Plates or Cylinders, of which the following is a specification.

10 This invention relates to an improved method of producing intaglio printing plates or cylinders, and has for its primary object to provide such a method whereby the production of such printing plates or 15 cylinders may be greatly expedited and whereby more accurate "color control" or color rendering with a marked improvement in the resultant printing over that which is possible in the use of methods now commonly employed may be attained.

It is another object of my present invention to provide such a method whereby the etched cavities in the surface of the printing plate or cylinder will be of uniform 25 depth for both the high-lights and shadows, thus resulting in the deposit of a uniform quantity of ink on the paper during the entire commercial life of the cylinders or plates as distinguished from the present 30 method wherein the high-lights gradually disappear from the printed sheet because the etched cavities are much shallower than the cavities for the shadows or darker portions of the print and therefore, wear away more 35 quickly so that in a relatively short period of time no ink will be deposited from these shallow cavities on the paper. As a result, I secure a much greater volume of production since the whole surface of the 40 copper plate or cylinder wears evenly due to the fact that all of the cavities are of the same depth.

It is also another object of my present improvements to provide such a method where- 45 in the ordinary half-tone and Benday re- 50 lief printing plates may be used in place of photographic positives for the production of the relief portions of the half-tone and Benday plates in the form of etched cavities in the surface of the final printing plate or cylinder of uniform depth.

I shall now first describe a preferred em- 55 bodiment of my new process or method and then subsequently describe an alternative thereof.

The impression or impressions for printing in color is first produced upon individual half-tone or Benday process plates in the same manner as now employed. After a satisfactory plate has been obtained for each 60 color, I then take this original plate corresponding to either yellow, red, blue and black respectively and black ink each re- 65 spective plate. Then I apply directly to each inked plate, a transparent material 70 and thus take an impression from each plate on grained, ground, or coated celluloid or other transparent impression receiving material. This provides a separate black proof on this celluloid or other transparent ma- 75 terial of each color.

This transparent material proof is used as a photographic printing medium and the impression thereof is transferred directly from each of these proofs to separate car- 75 bon tissue sheets by means of lights. The impression from each of said carbon tissue sheets is then transferred directly to the individual cylinders or final printing plates. Each carbon tissue corresponding to each 80 color is for each separate cylinder or plate.

In order to be able to duplicate cylinders to enable such duplicated cylinders to be substituted for the first cylinders, the same transparent material proofs can be used 85 again for new carbon tissues, to be applied to other cylinders or plates whereby duplicate cylinders or plates can be made.

This celluloid or transparent proof mate- 90 rial is a master sheet from which any de- 95 sired number of carbon sheets may be pro- 100 duced for the purpose of making any num- ber of duplicate cylinders or plates.

In the present state of the art, glass plates are used which require re-touching and if 95 broken, it is impossible to make an exact duplicate. But by the use of the celluloid proof, each carbon tissue will be printed exactly alike and hence each cylinder made therefrom exactly alike.

In the process at present commonly in use, photographic negatives are made, these are retouched, then photographic positives are made from these retouched negatives and then these positives have to be retouched. 105 Such retouching of the positive and nega- 110 tive prints is unsatisfactory because proper color rendering on the negatives and positives requires the highest type of skilled artists, and there are no establishments supply-

ing commercial printing plates and cylinders where printers might obtain work of this kind. On the other hand, any printer employing my new method can purchase the 5 half-tone and Benday process plates. Therefore, it will be seen that one of the prominent features of my present improvements resides in the application and use of half-tone and Benday process plates to the intaglio method of printing. Another objection 10 to the present method is that the retouching of the negatives and positives is not satisfactory because they are of continuous tone and therefore, the artist has 15 no gauge or measure by which to proceed and must depend upon his own judgment. The only retouching required in the present method is upon the etched plate or cylinder. The retouching on the copper plate or cylinder 20 is much more satisfactory than the retouching on positive and negative prints, such retouching of the etched cylinder corresponding to color photoengraving which I apply to intaglio printing.

25 Another advantage incident to the use of color half-tone and Benday process plates which is one of the oldest known methods of color rendering resides in the fact that color etchers are accustomed to arriving at 30 certain color schemes in terms of the different size or area of the dots or screen formations on such printing plates. In other words, I have succeeded in applying the 35 oldest and most satisfactory method of plate making to the most modern kind of printing.

In the case of intaglio printing, the impressions thus transferred to the cylinders or plates are then etched out in the surface 40 thereof. However, it is to be understood that my new method is not necessarily limited to intaglio printing, but can also be applied to "off-set" and photolithographic offset printing.

45 From the above, it will be noted that by means of this method, I eliminate entirely the necessity for all camera work, and all re-touching. In other words, negatives and positives are not made from the half-tone 50 or Benday plates. Consequently, I am enabled to maintain directly absolutely tone values and screen formations of the original plates thus proofed on celluloid or other suitable transparent material. I sometimes 55 find it beneficial to use in connection with the above described method, a screen on the carbon tissue before printing thereon.

As an alternative for the above described 60 method, I may take the original yellow, red, blue and black half-tone or Benday plates and make a black proof on celluloid or other transparent material for one color or each one of the four or more colors, and then photograph each of these black proofs, 65 this producing four negatives. From these

four negatives, I make a positive of each color print. This results in absolutely perfect control of the color as distinguished from the uncertain results obtained by the use of the present method, wherein it is necessary to re-touch the negative and positives. From the four positives thus obtained, I print upon the four separate carbon sheets by the same method as now in general use, and in connection therewith I may also use 70 a screen as above referred to in the description of the preferred embodiment of the invention.

From the foregoing it will be seen that by the production of intaglio printing plates 80 or cylinders by the present method using relief process printing plates such as half-tone and Benday plates, more uniform and consistent printing will be produced by reason of the fact that the etched cavities 85 are of uniform depth in both the highlights and shadows, thus depositing a uniform quantity of ink on the paper during the entire life of the cylinder or plate. The operation of etching, therefore, becomes 90 a mechanical operation requiring no great skill on the part of the etcher, since the cavities in reality are merely the inverted half-tone dots of the half-tone or Benday plate. I have found from practical experience that by reason of the uniform depth 95 of the etched cavities, the most satisfactory results are obtainable by an etching operation consuming less than one-half the time heretofore necessary in the production of 100 intaglio printing plates. As, in such printing plate the uniform depth cavities wear away evenly, duplication of the printing cylinders or plates for large quantity production work becomes unnecessary.

105 It is to be understood that the present process may be practiced with distinctly advantageous results in the expedition of the work, either as applied to monotone or multi-color printing. In other words, it will be evident from the foregoing description of my new method for the transfer of the impression from the original half-tone or Benday process plate or plates to the transparent proof material, and thereafter as described to the final plates or cylinders or printing plate or plates is greatly expedited and an appreciable saving in time 110 and labor is realized by the elimination of the necessity for re-touching positives and negatives, while, at the same time, more positive and correct "color control" or color rendering is attained with a corresponding improvement in the final multi-color impression. This is due to the fact that each cylinder or plate for each color, in case more 115 than one color is used, is an exact duplicate of each of the others and that by the use of a transparent impression receiving material for the transfer of the impression from 120 125 130

the black proof, of the half tone or Benday process plates to the carbon tissue sheet, all of the high lights and the sharp details are retained and not obliterated or lost, as is the case when the photographic process is used.

I claim:

1. An improved method of producing intaglio printing plates or cylinders which consists in first producing an impression upon a transparent impression receiving material from a relief process printing plate, then photographically reproducing the said impression from said transparent material on carbon tissue, then applying the carbon tissue upon the surface of the printing cylinder or plate, and then etching the surface of the cylinder or plate through said carbon tissue and producing uniform depth cavities therein.
2. An improved method of producing intaglio printing plates or cylinders which consists in first producing an inked impression from a half-tone printing plate upon a transparent impression receiving material, then photographically reproducing such inked impression from said transparent material on a carbon tissue sheet, and then etching through said carbon tissue sheet upon the surface of the printing plate or cylinder to produce uniform depth cavities therein for all parts of the image.
3. A method of producing intaglio printing plates for multi-color printing which consists in first producing an inked impression from each one of a plurality of relief process printing plates upon transparent impression receiving material, then photographically reproducing the respective impressions on separate carbon tissue sheets, then transferring the carbon tissue sheets to separate printing plates or cylinders, then etching the surfaces of the re-

spective plates or cylinders through said carbon tissue sheets for the purpose of printing in intaglio therefrom.

4. The method of producing intaglio printing plates or cylinders which consists in first producing an inked impression from a relief process printing plate upon transparent impression receiving material, then photographically reproducing the impression from said material upon a carbon tissue sheet having a screen printed thereon, then transferring the carbon tissue sheet to the surface of the plate or cylinder, and finally etching through the carbon tissue sheet to produce uniform depth cavities in the surface of the cylinder or plate for the purpose of printing in intaglio therefrom.

5. In the production of intaglio printing plates or cylinders, the steps which consist in photographically reproducing upon a carbon tissue sheet relief dots of a commercial half-tone printing plate and then etching the surface of the plate or cylinder through the carbon tissue sheet to produce uniform depth cavities therein for the purpose of printing in intaglio from the plate or cylinder.

6. In the production of intaglio printing plates or cylinders, the steps which consist in producing a photographic impression of the relief portions of a commercial printing plate upon a carbon tissue sheet without retouching, and then etching the surface of a printing plate or cylinder through said carbon tissue sheet to produce uniform depth cavities therein corresponding with the relief portions of the commercial printing plate for the purpose of printing in intaglio therefrom.

In testimony that I claim the foregoing as my invention, I have signed my name hereto.

WILLIAM EDWARD CROWE.
